UNITED STATES PATENT OFFICE.

JAMES McHUGH AND EUGENE F. INGLES, OF CHICAGO, ILLINOIS.

DESIGN FOR A LAMP.

Application filed October 24, 1927. Serial No. 23,870. Term of patent 3½ years.

To all whom it may concern:

Be it known that we, JAMES McHUGH and EUGENE F. INGLES, citizens of the United States, residing at Chicago, in the county of Cook and State of Illinois, have invented a new, original, and ornamental Design for a Lamp, of which the following is a specification, reference being had to the accompanying drawing, forming a part thereof.

The figure discloses a side elevational view of a lamp embodying my design. The shade portion in this figure is substantially rectangular in cross section and tapers inwardly from the base to the top thereof.

We claim:

The ornamental design for a lamp as shown and described.

EUGENE F. INGLES.
JAMES McHUGH.
